UNITED STATES PATENT OFFICE.

PATRICK P. LA MONTAGNE, OF BOURBONNAIS, ILLINOIS, ASSIGNOR TO PARAMOUNT
KNITTING COMPANY, OF CHICAGO, ILLINOIS, A CORPORATION OF ILLINOIS.

KNITTING-MACHINE.

1,325,644.

Specification of Letters Patent. Patented Dec. 23, 1919.

Application filed March 13, 1918, Serial No. 222,059. Renewed June 14, 1919. Serial No. 304,278.

To all whom it may concern:

Be it known that I, PATRICK P. LA MONTAGNE, a citizen of the United States, residing at Bourbonnais, county of Kankakee, 5 State of Illinois, have invented an Improvement in Knitting-Machines, of which the following description, in connection with the accompanying drawing, is a specification, like characters on the drawing representing like parts.

This invention relates to knitting machines of that type employing the so-called separate latch needle and the main object of the invention is to provide means for insuring the positioning of the yarn in the 15 path of the needle so that it will be caught by the hook and covered by the latch.

In knitting machines employing the ordinary type of pivoted latch needle the hook 20 is constructed so as to be entirely in front of the body of the needle, thereby making it possible to feed the yarn directly into the path of the descending hook with the ordinary method of feeding, and in the knitting 25 machines employing the spring beard needle the yarn is moved up beneath the beard of the needle so as to come within the hook. When, however, the knitting machine comprises the separate latch type of needle, 30 wherein the latch member reciprocates longitudinally with respect to the hook member in effecting the opening and closing movements of the needle, there is nothing in the needle structure or its operation which insures the yarn being properly positioned 35 and being covered by the latch prior to casting off.

In a prior application No. 205,980 filed December 7, 1917, there is disclosed as a specific embodiment of a broad means for effecting the desired result a bur wheel which works in conjunction with the set of separate latch needles and acts to position the 40 yarn properly in the needles.

The present invention discloses another 45 efficient means for effecting this same broad result. This means comprises a device or devices bodily movable toward and from the needle bed and acting upon the yarn receiving movement of each needle to press the yarn past the tip of the hook sufficiently to insure its being caught by the hook upon its retracting movement. More specifically 50 considered this means consists in the pro-

vision upon the usual sinkers of upwardly 55 and inwardly projecting arms provided with yarn contacting faces opposite the needle throats when in yarn receiving position and in the provision of means for actuating the sinkers at each side of a needle 60 when the yarn is fed thereto to project the sinkers just sufficiently to cause the yarn contacting faces of the arms thereof to press the yarn past the tip of the hook and hold it until caught by the hook.

These and other features and objects of the invention will appear more fully from the accompanying description and drawings and will be particularly pointed out in the 65 claims.

The drawings represent for the purpose of disclosing the invention a form of knitting machine of the circular type provided both with a set of cylinder needles and a set of dial needles, but it will be obvious that 70 the invention is not to be restricted to any particular type of knitting machine. So also, the drawings disclosed for the purpose of illustrating the invention the type of separate latch needle shown in the patent to 75 Pope & Randall No. 1,096,945, granted May 19, 1914, but it will also be obvious that the invention is not to be restricted to any particular type of separate latch needle.

In the drawings, 80
Figure 1 is a vertical transverse section of the upper portion of a knitting machine of the type disclosed taken chiefly on a plane passing transversely through the cylinder axis;

Fig. 2 is an enlarged detail showing a cylinder needle, a dial needle, a sinker and the immediately adjacent portions of the machine in position generally similar to that shown in Fig. 1;

Fig. 3 is a diagrammatic plan with the spacing exaggerated of a section of the cylinder needles, the sinkers, the yarn guide and yarn to show the position taken by the sinkers in effecting the position of the yarn, 90 the yarn guide being located above the path of the sinkers;

Fig. 4 is a plan of a sinker cam suitable for effecting the operation of the sinkers illustrated in Fig. 3;

Fig. 5 is a view similar to Fig. 3 showing the arrangement when the yarn guide is located in the path of the sinkers;

Fig. 6 is a view similar to Fig. 4 showing the cam path as adapted for the operation illustrated in Fig. 5.

The knitting machine illustrated in the drawings is particularly adapted for the knitting of ribbed leg stockings and contains provision therein for the knitting of plain, circular and ribbed work but as the details of such machines are well known and familiar to those skilled in the art and are not involved in the present invention they are not illustrated and described save so far as is necessary for a disclosure of the present invention.

15 The frame of the machine supports a top bed plate 1 and includes a standard 2 containing a bearing for the main power transmitting shaft 3. The bed plate is provided with a depending tubular bearing 4 in which 20 is mounted the tubular needle cylinder carrier 5.

The cylinder carrier 5 is surrounded by and supports the needle cylinder 6 which is longitudinally grooved on its outer periphery in the usual manner to receive and 25 guide the cylinder needles.

The cylinder needles each comprise a hook member 7 and a latch member 8. The latch member rides in a narrow groove 9 in the 30 needle cylinder and the hook member in a wider superimposed groove 10.

Each hook member as disclosed in the aforesaid Patent No. 1,096,945 is provided with the usual hook 11 and butt 12 and is 35 transversely and longitudinally slotted beneath the hook for the passage of the latch. Each latch has a bent shank 13 frictionally engaging the walls of its slot and a head 14 riding through the slot in the hook member. 40 Coöoperating shoulders on the hook and latch members secure the reciprocation of the latch member from the hook member to effect the opening and closing movements all in a well known and familiar manner to this type of 45 needle.

The butts 12 of the hook members are guided between the bars 15 of a skeleton cylinder and contact with the usual cams for effecting the proper reciprocation of the 50 needles. The lower or projecting cam 16 is illustrated on the cam carrier 17 mounted for rotary movement in the bed plate 1. This cam carrier 17 is locked to and rotates with the gear ring 18 also mounted for rotation 55 in the bed plate 1. This gear ring on its lower surface is provided with beveled teeth 19 by means of which it engages and is driven by a beveled gear 20 on the shaft 3.

The machine is shown as provided with 60 sinkers which except for the embodiment therein of the novel features of this invention are of a well known type. In performing their sinking function the sinkers are withdrawn at the knitting point and there- 65 after moved inwardly to carry the loops over

the hooks of the needles and are then withdrawn slightly in a well known manner.

These sinkers 21 are radially and slidingly mounted at their inner ends in an annular sinker cylinder 22 secured by set screws 23 to the interior of the needle cylinder 6 and at their outer ends in an annular sinker guide 24 also secured by set screws 25 to the exterior of the needle cylinder 6. A sinker cam ring 26 in which is formed or to which is attached the cam for securing the operation of the sinkers is provided with a depending annular flange 27 which rests in an annular recess in the annular sinker guide 24 so that the sinker cam ring is rotarily mounted 80 thereon. The rotary movement of the sinker cam ring with the gear ring 18 is secured by a pair of oppositely disposed posts 28 and 29 projecting upwardly from the gear ring 18 and engaging projections 30 and 31 respectively from the sinker cam ring.

The type of knitting machine shown for the purpose of illustration is equipped for performing ribbed work and for that purpose a dial and a set of dial needles are 90 shown. In the construction illustrated the dial mechanism is supported from the sinker cam ring 26. For this purpose oppositely disposed posts 32 and 33 are secured in the flanged portion of the sinker cam ring 26 and these posts carry a yoke 34 provided with a central hub 35 through which the dial shaft 36 extends. This dial shaft carries a usual form of dial 37 radially grooved on its upper surface at 38 and 39 to receive and carry respectively the latch members 40 and the hook members 41 of the separate latch dial needles of the general type shown, for example, in the patent to Pope & Randall No. 1,096,946 granted May 19, 1914. The butts 42 of the hook members of these dial needles are operated by the dial cam 43 supported on the dial shaft 36 in the usual manner.

For simplicity of disclosure a single yarn feed is shown. The yarn 44 passes down through a guide eye 45 in the yoke 34 through a yarn guide 46 carried by the sinker cam ring 26 and located immediately above the sinkers at the knitting point.

This description of the type of knitting machine illustrated will be sufficient to disclose to those skilled in the art the general construction and operation of the machine which has been selected for the purpose of 120 disclosing the present invention.

In the case of the separate latch type of knitting machine needle it is desirable that the needle should have a short throw and also as short a slot in the hook member as possible in order that the needle may be rigid. This results in bringing the cheek 47 of the hook member well up toward the hook and also requires that it shall be high or of maximum transverse cross section 125 130

properly to guide the latch member. But with a high cheek thus located when the yarn is fed to the needle the yarn will be held out by the cheek adjacent the feeding point so that it is liable not be caught by the hook. It is desirable, therefore, and necessary if the needle is constructed in its best form, to provide means for positively moving the yarn when fed into the path of the hook of the dial needles. When both the dial and cylinder needles are in operation, as in knitting ribbed work, then the dial needles act to draw the yarn into the path of the hook of the cylinder needles. But when the dial needles are out of operation or when the machine is not provided with dial needles then it becomes desirable or necessary to provide means for positively moving the yarn when fed into the path of the hook member of the needle.

For this purpose the invention provides means which are bodily movable toward and from the needle bed and which act upon the yarn receiving movement of the needle to press the yarn past the tip of the hook and thus insure its being caught by the hook. Such a means may, as herein illustrated, be conveniently embodied in the usual sinkers employed in the machine one form of which is illustrated herein. For that purpose each沉器 may be provided with an upwardly and inwardly projecting arm having a yarn contacting face opposite the needle throat when the needle is in its yarn receiving position so that when the yarn is fed to the needle it will come opposite the yarn contacting face of this arm. If the desired means is thus embodied in the sinkers it follows that the sinkers must be given a movement somewhat different from or additional to that required solely for the performance of the sinking function. Hence the cam for the sinkers is disclosed as altered or modified to cause the sinkers at each side of the needle to which the yarn is fed first to retract as usual next to project just sufficiently to cause the yarn against the contacting face of the arm to be pressed past the tip of the hook and held until caught by the hook, next to retract slightly and then to project as usual to effect their usual function. This additional slight projecting and retracting movement given to the sinkers over their ordinary movements is necessary because otherwise the yarn would be crimped by the sinkers in succession and would thus prevent the proper drawing in of the loops.

When the machine contains as illustrated a set of dial needles operating in conjunction with the cylinder needles at required times for making ribbed work then the sinkers must also be so constructed as to provide for the operation of the dial needles. For this purpose the arm which is added to the

sinker is so constructed as to leave a recess between it and the body of the sinker sufficient for the operation of the dial needle.

In the specific embodiment of the invention shown each沉器 is provided with a butt 48 riding in a cam groove 49, the walls of which obviously may not be continuous as illustrated diagrammatically in Fig. 4 but are located wherever necessary to give the required movements. Each沉器 is provided with an arm 50 projecting upwardly from the body of the沉器 and inwardly or forwardly toward the needles. When the dial needles are employed this arm 50 springs outwardly and then forwardly to leave a recess 51 for the passage of the dial needles when in use so that there may be no interference with the dial needles. This arm presents a yarn contacting face 52 which when the needle as 7 is in yarn receiving position comes opposite the throat of the needle.

Referring now to Fig. 3 of the drawing which illustrates the sinkers and needles in a diagrammatic manner and much exaggerated as to spacing the operation will be clear. The cam for operating the sinkers is constructed symmetrically with respect to the line 53. The沉器 cam and yarn guide 46 are indicated as moving in the direction of the arrow 54. In the usual operation of the sinkers the cam acts to retract the sinkers from the inwardly projected sinking position *a* gradually until the sinkers are well retracted clear of the needles as from *e* to *l* past the knitting point and then the sinkers are gradually projected again to the position *p* corresponding to the position *a*. If the machine is rotating in the opposite direction the reverse action takes place.

In the present invention the needle in the position *7^a* is at its highest point of projection and as the yarn extends from the preceding needles wrapping around the cylinder to the yarn guide 46 it is held out of the path of the hook, as the needle moves slightly downward into its position *7^b*, by the cheek of the needle and consequently the yarn would not be caught by the hook as the needle is retracted. Consequently the cam for actuating the sinkers is so formed that as the needle starts downward the sinkers are projected inwardly slightly at each side of the needle to cause the yarn contacting faces of the arms 50 to force the yarn into the throat of the hook and past the tip. In Fig. 3 the sinkers *h* and *i* are shown as having moved inwardly carrying the yarn into position and the needle in position *7^c* is moving downwardly. As this action continues the sinkers are retracted as the needle reaches the position where the latch closes over the hook until the sinkers are back in their normal position at *k* and *l*. Then

the sinkers are moved inwardly again in the usual manner to perform their sinking function. As the cam is made symmetrical it follows that if the rotation takes place in 5 the opposite direction the action will be similar but reversed.

The inward projection of the sinkers is comparatively slight as shown at positions *h* and *i* and only sufficient to cause the yarn 10 to be pushed beneath the tip of the hook and then the sinkers are immediately retracted because if the sinkers were projected too far inwardly and were not immediately withdrawn the yarn would be so crimped that, as 15 the needles draw down, the loops could not be pulled into the fabric and the yarn might be broken.

A suitable form of sinker cam is illustrated in Fig. 4 wherein the section 55 of 20 the cam path is that designed for the sinkers when in their inner projected position for pushing the yarn into the path of the hook of the needle.

In the construction illustrated in Fig. 3 25 the yarn guide 46 is assumed to be above the path of the sinkers and above the path of the arms 50. If it is desired to bring the yarn guide closer to the hook and in a lower plane this can be done by providing a 30 more extended retraction of the sinkers at the knitting point so that they will pass behind the yarn guide and this arrangement is shown in Figs. 5 and 6. The only difference is that the cam path 49 at the sections 35 56 is arranged to retract the sinkers more than in the other case at the section 57 to give them a more extended projection to carry them to the same position for pushing the yarn beneath the hook illustrated in 40 Fig. 3.

It will thus be seen that in either case the sinkers are successively retracted at the knitting point, then successively projected partway to place the yarn in the throat of 45 the needle receiving the yarn, then successively retracting again, and then successively projected again to secure their usual function. Consequently the precise number of sinkers engaged at one time in pushing 50 the yarn into the path of the needle may vary, one being sufficient if the machine always rotates in one direction, two being sufficient if the machine rotates in either direction, and more being permitted or required 55 so long as they are retracted in time to prevent undesirable crimping of the yarn.

When a set of dial needles is employed 60 the dial needles themselves act to draw the yarn into position beneath the hook of the cylinder needles and at this time the arms 50 of the sinkers are not necessary but their operation is harmless and as has been explained a recess 51 is provided in each

sinker to permit the excursions of the dial 65 needles to take place.

Having fully described my invention, what I claim as new and desire to secure by Letters Patent is:

1. A knitting machine comprising a needle cylinder, a set of separate latch needles mounted therein, a set of sinkers radially reciprocable between said needles, upwardly and inwardly projecting arms on said sinkers provided with yarn contacting faces 70 opposite the needle throats when in yarn-receiving position, and means acting to retract the sinkers at the knitting point then to project the sinkers just sufficiently to cause the yarn contacting faces of one or 80 more thereof to press the yarn past the tip of the hook of the needle and hold it until caught by the hook of the needle as the needle retracts, then to retract the sinkers thus projected, and then again to project 85 the sinkers to effect their usual function.

2. A knitting machine comprising a needle cylinder, a set of separate latch needles mounted therein, a dial, a set of dial needles mounted therein, a set of sinkers radially reciprocable between said cylinder needles, upwardly and inwardly projecting arms on said sinkers provided with yarn-contacting faces opposite the needle throats when in 90 yarn-receiving position and provided with recesses beneath said arms in line with the corresponding dial needles to permit the projection of the dial needles without interfering with the action of the sinkers, means acting to retract the sinkers at the 95 knitting point then to project the sinkers just sufficiently to cause the yarn contacting faces of one or more thereof to press the yarn past the tip of the hook of the cylinder needle and hold it until caught by the hook 100 of the cylinder needle as the cylinder needle retracts, then to retract the sinkers thus projected, and then again to project the sinkers to effect their usual function.

3. A knitting machine comprising a needle 110 bed, a set of separate latch knitting needles mounted therein and means bodily movable toward and from said bed and acting upon the retracting movement of each needle to press the yarn past the tip of the needle 115 hook and insure its being caught by the hook.

4. A knitting machine comprising a needle bed, a set of separate latch knitting needles mounted therein and means bodily movable 120 toward and from said bed and acting upon the retracting movement of each needle to press and hold the yarn in the path of the hook until the latch has closed over the hook.

5. A knitting machine comprising a needle cylinder, a set of separate latch needles mounted therein, a set of yarn-controlling devices radially reciprocable between said

needles and provided with yarn contacting faces opposite the needle throats when in yarn-receiving position, and means acting to retract the said devices at the knitting point 5 then to project one or more of said devices just sufficiently to cause the yarn contacting faces thereof to press the yarn past the hook

of the needle as it retracts to receive the yarn and hold the yarn until caught by the hook and then to retract said devices out of 10 contact with the yarn.

In testimony whereof, I have signed my name to this specification.

PATRICK P. LA MONTAGNE.
